United States Patent Office.

EDWARD SEELEY, OF SCRANTON, PENNSYLVANIA.

Letters Patent No. 85,081, dated December 15, 1868.

IMPROVEMENT IN WASH-BOILERS.

The Schedule referred to in these Letters Patent and making part of the same.

To all whom it may concern:

Be it known that I, EDWARD SEELEY, of Scranton, county of Luzerne, State of Pennsylvania, have invented a new and improved Wash-Boiler; and I hereby declare the following to be a full, clear, and exact description thereof, which will enable those skilled in the art to make and use the same, reference being had to the accompanying drawings, making a part of this specification, in which—

Figure 1 is a perspective view.

Figure 2 is a vertical longitudinal section thereof, showing the contracting passages through which the water rises, and also the aperture through which it is discharged.

Figure 3 is a vertical transverse section on line $x-x$ of fig. 1, showing the deflecting-plate, and the chamber through which the water ascends to the discharge-aperture.

Similar letters of reference indicate corresponding parts.

This invention relates to boilers in which clothes are washed by means of jets of water, and by the force of steam, which is generated therein while the process of cleaning them is being performed; and

It consists in the construction of the deflecting-plate within and near the bottom of the boiler, and in its arrangement with reference to the ascending-water passages; and, further, in the construction of the passages through which the water ascends from the bottom of the boiler to the surface of the contents of such boiler, as will be more fully described hereafter.

Experience has demonstrated the fact that the efficiency of this class of boilers or washers depends, to a great extent, upon the force or momentum which is given to the jets of water which fall upon the surface of the clothes while being cleaned, and my invention is designed, amongst other things, to remedy a defect existing in those boilers now in use, in this respect, by providing a deflecting-plate at the bottom of such boiler, and arranging it in such a manner that only so much water shall come in actual contact with the bottom of the boiler as is necessary to preserve it from injury, and to furnish sufficient steam to induce the upward flow of the bulk of the water, the direction to which is given by the curved form of the deflecting-plate.

A, in the drawings, represents a boiler or washer, which is rectangular in form, but which may be of any of the forms adapted to use for this purpose, and it is to be constructed in the usual or any convenient manner, and of sheet or cast-metal.

B is a deflecting-plate, which is of the curved form shown in fig. 3, by means of which construction the largest portion of the water is directed upward through the passages formed for that purpose. This plate is of the proper dimensions to nearly fill the boiler in the direction of its greatest length, while its edges pass under the lower edge of the plates C, which form the water-ascending passages, but do not touch the sides

of the boiler, but terminate at a distance therefrom sufficient to leave a passage for the steam which is generated below such plate to ascend, in doing which it passes the edge of the plate with great rapidity, thus inducing or compelling the water to take the same direction, which operation is facilitated by the construction of the plate, and by its peculiar configuration.

It will be observed that the arrangement of the above-described plate is such, that, when in operation, very little water can settle upon the bottom of the boiler, by which means the space below the deflecting-plate is converted into a steam-chamber.

C are plates, of metal, which, together with that portion of the boiler which they cover, form the ascending-passages for the water. They consist of plates or sheets, which, at their ends and at their top edges, are soldered or otherwise secured to the plates or sides *a* of the boiler, in such a manner as to leave the passage, through which the water ascends, a gradually-decreasing one, from its bottom to its top. These plates extend from near the bottom of the boiler, as shown in fig. 3, upwards for about one-third that of the height of the boiler, for which distance they form but one passage or chamber, but at which point they terminate, and for the remainder of the distance they are divided into the form of pyramidal chambers or passages, through each of which water passes to the apertures *a a*, where it is discharged to the surface of the contents of the boiler.

D is the cover of the boiler, which is of the usual construction, and is held in its closed position by clasps or buttons, in any convenient manner.

E is a rim, formed upon the top edge of the boiler, which is so constructed as to form a trough or conduit entirely around the upper edge thereof, into which any water which may be forced up around the edge of the cover will be deposited, and by which such water will be conducted to the pipe F.

F is a vertical pipe, which is connected at its lower end, by means of a short horizontal pipe or portion of itself, with the body of the boiler, at some point below the surface of the contents of the same, while its upper end communicates with the trough or conduit formed upon the upper edge of the boiler, and is for the purpose of conducting water from such conduit to the boiler.

G are buttons or clasps, for securing the cover D of the boiler in position when in use. They consist of pieces of metal, hinged to the upper edge of the boiler in such a way, that, when turned down in the manner shown in the drawings, they rest upon and hold the cover in contact with the boiler; but they may be turned up, and thus relieve such cover, and allow it to be readily removed.

Having thus described my invention, What I claim, and desire to secure by Letters Patent, is—

1. The dome-shaped deflecting-plate, with its up-

wardly-inclined edges, substantially as shown and described.

2. The arrangement of the deflecting-plate B, with reference to the plates C C', and to the plates forming the walls of the boiler, as a consequence of which, only a small amount of water is allowed to pass below such deflecting-plate when the boiler is in use, substantially as shown and described.

3. The within-described construction of the passages for the ascending water.

In testimony whereof, I have signed my name to this specification, in the presence of two subscribing witnesses.
